UNITED STATES PATENT OFFICE.

ALFRED L. SEDDON, OF WATERFORD, NEW YORK.

SAFETY ATTACHMENT FOR CLOTH-FOLDING MACHINES.

1,198,588.

Specification of Letters Patent. Patented Sept. 19, 1916.

Application filed December 5, 1914. Serial No. 875,633.

To all whom it may concern:

Be it known that I, ALFRED L. SEDDON, a citizen of the United States, residing at Waterford, county of Saratoga, and State of New York, have invented certain new and useful Improvements in Safety Attachments for Cloth-Folding Machines, of which the following is a specification.

The invention relates to such improvements and consists in the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of a cloth-folding machine provided with my improved safety attachment. Fig. 2 is a similar view of the attachment and the means for operating the attachment, showing the belt-shifting rod in cross-section, a portion of the frame of the machine being indicated by broken lines. Fig. 3 is a view in elevation of the right-hand end of the machine, as shown in Fig. 1, omitting various parts not necessary for an understanding of the invention. Fig. 4 is a top plan view of the attachment and neighboring parts of the machine.

The invention relates to cloth-folding machines of the type wherein a long strip or web of cloth is laid back and forth in folds upon a table by means of folding-blades carried by an oscillating arm.

The object of the invention is to safeguard the operator of such a machine by making it practically impossible for the operator to start the machine except when the movable parts are in such position that the initial movement of the folding-blades will be in a direction away from the operator. In beginning the folding of a newly inserted web of cloth in such a machine, it is necessary for the operator to hold by hand the first inserted end of the web, while the first fold of the web is being laid upon the table by means of the folding-blades; and if, in starting the machine to begin the folding of a newly inserted web, the first movement of the folding-blades is toward the operator, there is danger of the opera-

tor's hands being engaged and injured by the folding-blades. 55

Referring to the drawings wherein the invention is shown in preferred form, 1 is the frame of the machine, and 2 is the main drive-shaft connected by belt, 3, and suitable pulleys with an intermediate shaft, 4, 60 which shaft, 4, is connected by means of a belt, 5, and suitable pulleys, with a crank-shaft, 6, each of the shafts, 2, 4, and 6 being rotatively mounted in suitable bearings on the frame of the machine. A crank-arm, 7, 65 on the crank-shaft, 6, is connected by a rod, 8, with an oscillating lever, 9, pivoted at its lower end at 10, upon the frame of the machine, upon the upper end of which lever, 9, are mounted the cloth-folding-knives, 11. 70

The web of fabric, 12, is led into the machine through a tension-device, 13, from which it passes down between the knives, 11, and by the reciprocating movement of the knives, 11, is laid back and forth in folds 75 upon the table, 14. As the cloth is laid back and forth in folds upon the table, 14, the folds are successively clamped between the end-portions of the table, 14, and the respective clamps, 15, the clamping of the folds 80 being accomplished by a vertical rocking movement of the table, 14, by suitable mechanism, the operation of which it is unnecessary to herein describe.

The main-drive-shaft, 2, has mounted 85 thereon a fixed pulley, 16, and an idle pulley, 17, and is adapted to be driven by means of a belt, 18, which can be shifted at will from one to the other of said pulleys by means of a belt-shifter, 24, fixed upon the 90 end of a rod, 19, mounted in slideway-bearings in the frame of the machine, and adapted to be reciprocated by means of the hand-lever, 20, fulcrumed at 21, upon the frame of the machine. 95

The construction above described is that found in a well-known type of cloth-folding machine, and will be fully understood by those skilled in the art.

In inserting a new web, the end of the 100 web is led from the tension-device, 13, between the knives, 11, to the front end of the machine, which is the right-hand end as viewed in Fig. 1. The end of the web is then drawn by the hand of the operator 105 down upon the front end of the table, 14, at

22, and is held in such position by one hand of the operator, while with his other hand he operates the hand-lever, 20, to shift the belt, 18, from the idle pulley, 17, to the fixed 5 pulley, 16, to start the machine, the operation of the machine being discontinued at the completion of the folding of each web. The operator can thus safely hold the end of the web until the first fold is laid upon the 10 table, 14, provided the initial movement of the folding-knives, 11, is in a rearward direction, that is, away from the operator; but if the initial movement of the folding-knives is toward the operator, there is great 15 danger of the knives striking and injuring the operator's hands.

In carrying out my invention I fix upon the belt-shifting-rod, 19, a beveled offset, 23, and I mount in a slideway-bearing, 25, on 20 the frame of the machine a reciprocatory rod, 26, having on one end a yielding latch, 27, yieldingly controlled by a spring, 28, which latch is adapted to be reciprocated by the reciprocating movement of the rod, 26, 25 into and out of the path of said offset, 23. The other end of the rod, 26, is connected by means of a lever, 31, fulcrumed at 32, on the frame of the machine, and a pitman, 29, with an eccentric, 30, fixed upon the crank- 30 shaft, 6.

In the operation of the machine the eccentric, 30, causes a reciprocating movement of the rod, 26, by each revolution of the crank-shaft, 6, which reciprocating movement of 35 the rod, 26, imparts a similar reciprocating movement to the yielding latch, 27, which, so far as this movement is concerned, is in effect a part of the rod, 26. The position of the eccentric, 30, on the crank-shaft, 6, is 40 such that during the movement of the belt-operating lever, 9, toward the front end of the machine, the yielding latch, 27, is located in the path of the offset, 23, on the belt-shifting rod, 19; and during the rearward movement of the belt-operating lever, 9, the latch, 27, is withdrawn from the path of said offset, 23. It will thus be seen that the machine can be stopped at any time during the rearward movement of the lever, 9, 45 by shifting the rod, 19, to move the belt from the fixed pulley, 16, to the idle pulley, 17, without engagement of the beveled offset, 23, with the yielding latch, 27; and that if the machine is so stopped, the yielding latch, 50 27, being out of the path of the offset, 23, offers no obstruction to the return movement of the rod, 19, whereby the belt is shifted from the idle pulley, 17, to the fixed pulley, 16, to again start the machine; and that in 55 so starting the machine, the initial movement of the lever, 9, and blades, 11, will be in a rearward direction away from the operator. If, however, the machine be stopped during the forward movement of the lever, 60

9, and blades, 11, the latch, 27, will then be 65 located in the path of the offset, 23, but will yield and be forced back by the beveled side of said offset, permitting the rod, 19, to be operated to shift the belt from the fixed pulley, 16, to the idle pulley, 17; but as soon as 70 the offset, 23, has passed the latch, 27, the latch will automatically spring back into the path of return movement of the offset, 23, and form a positive stop to prevent a return movement of the rod, 19, to start the machine. The latch, 27, thus prevents the operator from starting the machine at a time 75 when the initial movement of the rod, 19, would be toward the operator; and in such case, the operator operates the machine by 80 hand through the medium of the lever, 9, or crank-arm, 7, until the lever, 9, is in a position where the initial movement of the machine when started by means of the belt, 18, will cause the lever, 9, and blades, 11, to 85 move in the rearward direction.

In Fig. 2 the parts are shown in such a position that the latch, 27, is withdrawn from the path of the offset, 23; while in Fig. 4 the parts are shown in such a position that the latch, 27, is located in the path of the offset, 23, in which position it prevents a return movement of the belt-shifting-rod, 19.

What I claim as new and desire to secure 95 by Letters Patent is—

1. In a machine of the class described, and in combination, a reciprocatory cloth-laying member; a drive-shaft; mechanism for starting and stopping the operation of said drive-shaft comprising in part a movable member having a beveled offset; a reciprocatory member having a yielding latch movable into and out of the path of said offset and adapted when in the path of said offset to yield to a stopping movement of the member having the beveled offset and to prevent a starting movement thereof; and operating connections between said drive-shaft and said cloth-laying mechanism and 105 said reciprocatory member, whereby said latch is maintained in the path of said offset during the forward movement of the cloth-laying mechanism and is held withdrawn from the path of said offset during the rearward movement of the cloth-laying mechanism. 110

2. In a machine of the class described, and in combination, reciprocatory cloth-laying mechanism; a crank-shaft having a crank 120 connected with said cloth-laying mechanism; a belt-driven shaft connected with said crank-shaft; belt-shifting mechanism comprising in part a reciprocatory member having a beveled offset; a reciprocatory rod having a yielding latch adapted to be carried by said rod into and out of the path of said offset and adapted when in the path of said 125

offset to yield to a stopping movement of the belt-shifting mechanism and to prevent a starting movement thereof; and an eccentric fixed upon said crank-shaft in connection with said reciprocatory rod in a position to maintain said latch in the path of said offset during the forward movement of the cloth-laying mechanism and to hold said latch withdrawn from the path of said offset dur-

ing the rearward movement of the cloth-laying mechanism.

In testimony whereof, I have hereunto set my hand this 19th day of November, 1914.

ALFRED L. SEDDON.
